WHISTLE AND THE LIKE

Filed April 19, 1932

UNITED STATES PATENT OFFICE

ARTHUR L. BRIDGHAM, OF BOSTON, MASSACHUSETTS, ASSIGNOR TO CHARLES H. SHERBURNE, OF BOSTON, MASSACHUSETTS

WHISTLE AND THE LIKE

Application filed April 19, 1932. Serial No. 606,138.

The invention relates to an improvement in whistles or like instruments in which sound is produced by the vibration of a contained column or body of air and which vibration 5 is generated by the application of a gaseous fluid such as air or steam under what may be termed a sounding pressure.

The object of the invention is to provide means whereby a proper sounding pressure 10 upon the instrument may be obtained with a very small amount of air or steam relatively to the size of the instrument.

The invention can best be seen and understood by reference to the drawing in which 15 an embodiment thereof is shown applied to a whistle, and in which—

Figure 1 is a front elevation of the whistle.

Fig. 2 is a cross section on the line 2—2 of Fig. 1, and

Fig. 3 shows partly in vertical cross section and partly in front elevation a slightly modified form of the whistle applied to a valve casing incidental to an air brake system, in connection with which a whistle is 25 commonly employed.

Referring to the drawing:—

1 represents the body of the whistle preferably tubular in form. The top end of said body is closed by a snugly fitting block 2. 30 The opposite or lower end of the body 1 is left open. Arranged opposite this end and separated therefrom by a suitable air space 3 is a casing 4 preferably tubular in form the same as the body 1. Contained within this 35 casing is a block 5 which is joined to the block 2 by a connecting rod 6. The two blocks and connecting rod are preferably integral. The lower end portion 7 of the block 5 fits snugly within the casing while the upper end 40 portion 8 thereof is of less diameter than the interior of the casing leaving between it and the casing an annular space 9 which communicates with the air space 3 and opposite end of the body 1 by way of an annular port 10. 45 Communicating with the annular space 9 are intersecting cross passages 11 extending through the block 5. Entrance is had to these passages by way of a passage 12 which extends through a bushing 13 screw-threaded to 50 fit within the lower end portion 7 of the

block 5. The bushing 13 is borne by an injector block 14. Extending laterally through this block is a passage 15 connecting at its ends with the outer air. Screw-threaded to fit within the lower end portion of the block 55 14 is a nozzle 16 with tip preferably contained within the passage 15 below the entrance to the passage 12, the passage 17 through the nozzle being in alignment with the passage 12. The nozzle is borne by a 60 block 18 of which it forms preferably an integral part. This block is interiorly threaded to receive a connection (not shown) from any suitable source of gaseous pressure.

The operation is as follows: Gaseous pressure induced to pass through the nozzle will induce a flow of atmospheric air entering by way of the passage 15 to flow upwardly through the passage 12 into the passages 11 and space 9 forming a compression chamber, 70 and thence through the port 10 across the air space 3 to impinge upon the end of the body 1 for vibrating the air column within it.

In as far as the objective result is concerned the operation is the same as in the 75 case of an ordinary whistle or similar instrument such as an organ pipe. The means for accomplishing the objective result, is, however, different in the sense that an inflow of atmospheric air is caused by the operation of 80 the injector to constitute the essential sounding pressure upon the body of the instrument. This can perhaps be better appreciated by a consideration of the fact that if the amount of air or steam under pressure induced to 85 pass through the nozzle was alone relied upon and all atmospheric air shut off, the sounding pressure on the body of the instrument would be entirely inadequate and no appreciable sound, if any, would result. Under the same 90 conditions, however, with the same amount of air or steam passing through the nozzle, if then atmospheric air is admitted the sounding pressure upon the instrument will be entirely adequate to provide sound of great 95 volume and intensity.

With a whistle of about the same general size as that shown in the drawing and with an opening through the nozzle of one sixteenth of an inch and under an entering pres- 100

sure varying from 20 pounds to 120 pounds with a nozzle aperture of $\frac{1}{16}$ of an inch a sounding pressure was obtained entirely adequate for operating the instrument. Even 5 with the lowest pressure the results achieved were entirely adequate although the intensity and volume of sound was somewhat increased as the pressure increased.

The invention lends itself to any situation 10 where there is need of sounding a whistle or similar instrument with as little applied pressure as possible. An instance of such is an air brake system having a whistle and where there is great need of conserving the air in 15 the system and dissipating it as little as possible when the whistle is blown. The result has been the use of a very weak whistle for the reason that so little air could be used. With a less amount of air than ordinarily 20 used for blowing the whistle in an air brake system one is enabled by admitting an inflow of atmospheric air to obtain a sounding pressure sufficient to provide a whistle that can be heard at a very long distance, and will 25 meet all demands brought to bear upon it.

An example of the application of the present invention to the brake system is shown in Fig. 3. Here for purposes of expediency the whistle is made a little different from the 30 whistle shown in Figs. 1 and 2 although the principle remains the same, and is simply illustrative of the fact that the structural form of the whistle or instrument may be essentially changed without departing from the 35 essential invention. In other words, for example, the injector may be some distance removed from the place where the sounding pressure is applied to the body of the instrument.

40 In Fig. 3 *a* represents a valve casing commonly employed in connection with a brake system and upon which heretofore a whistle has been mounted and operated by a sounding pressure obtained from air within the brake system. The same casing is retained, and mounted upon this casing to form practically an integral part thereof is the block 20 bearing the injector nozzle 21. Screw-threaded to fit upon the base of the nozzle is the injector block 22 and upon this block the body 23 of the whistle is mounted, the block fitting snugly within the lower end of said body. 45 24 represents the entering passage for atmospheric air, the passage extending through the block 22 and that portion of the body of the whistle within which the block fits. The outer or top end of the body of the whistle is open. Arranged above this end and separated from it by a suitable air space 25 is a casing 26. 50 Contained within this casing is a block 27 which is joined to the injector block 22 by a connecting rod 28. The upper end portion of the block 27 fits snugly within the casing. The lower portion thereof is of less diameter 55 than the interior of the casing leaving be-

tween it and the casing an annular space 29 which communicates with the air space 25 and end of the body 23 by way of an annular port 30. Communicating with the annular space 28 are intersecting cross passages 31, 70 extending through the block 27. Entrance is had to these passages by way of a passage 32 which extends through the rod 28 from the chamber of the injector block 22 where atmospheric air is admitted.

The construction is substantially the same as first described, although the arrangement is quite different especially in the fact that the entering air passing through the rod 28 is at a point some little distance removed from the point where the sounding pressure is applied to the body of the instrument. The operation is the same as before. Pressure induced to pass through the nozzle will cause a flow of atmospheric air entering by way of the passage 24 to flow upwardly by way of the passage 32 into the passages 31 and space 29 and thence through the port 30 across the air space 25 to impinge upon the end of the body 23 for vibrating the air column within it.

Having thus fully described my invention, I claim and desire to secure by Letters Patent of the United States:—

In an instrument of the type specified, in combination, spaced casing portions, one of said casing portions having an air chamber, the other of said casing portions having an opening to the atmosphere and a compression chamber, said other casing portion having a passage connecting said opening and compression chamber, and a nozzle adapted to direct fluid under pressure into said passage and cause air to be drawn through said opening into said passage, said other casing portion having means for directing fluid under pressure from said compression chamber toward said air chamber.

ARTHUR L. BRIDGHAM.
